POLISHING MACHINE FIXTURE

Jay H. Gould, Detroit, Mich., assignor, by mesne assignments, to Houdaille-Hershey Corporation, Detroit, Mich., a corporation of Michigan

Application March 25, 1938, Serial No. 198,066

3 Claims. (Cl. 51—76)

My invention relates to the polishing art, particularly the polishing of objects such as impact bars for bumper structures for automotive vehicles. In polishing machines for this work the bumper bars to be polished are supported on a belt or other suitable conveyer to be carried through the fields of polishing wheels, the bars being mounted to be carried longitudinally in engagement with the polishing wheels. Sometimes the bumper impact bars have slight twist or edge warp or other condition which may prevent their proper and accurate application to the polishing wheel for accurate and uniform polishing thereof unless the bars may readily adjust themselves for proper application to the polishing wheels throughout their extent.

The object of this invention is, therefore, to provide improved support units or fixtures which may be mounted on the conveyer to be spanned by the bars to be polished and which fixtures or supports are flexible or yieldable to permit the bars to move sideways and sway from one side to the other so that any slight twist, edge warp, or other irregularity may be properly applied to the polishing wheels. To this end, the fixtures or supports are preferably mounted on soft rubber blocks or cushions which will make the fixtures readily yieldable both vertically and laterally so that the bars may be accurately applied throughout their extent to the polishing wheels.

An efficient embodiment of my invention is shown on the drawing, in which drawing:

Figure 1 is a side elevation of a conveyer structure with my improved supporting units or fixtures thereon and bars to be polished supported thereon;

Figure 2 is an enlarged side elevation, partly in section, of one of the units; and

Figure 3 is an enlarged cross-section of the yieldable supporting frame for the units.

On the drawing, 10 represents more or less diagrammatically a belt or other conveyer traveling in the direction of the arrow. On this conveyer are mounted the supporting units or fixtures U at properly spaced intervals to be spanned by the objects to be polished, as for example automobile bumper impact bars B. Each of the units shown has a resilient and yieldable base structure comprising upper and lower plates 11 and 12, preferably of metal such as steel, with blocks or cushions 13 of resilient material such as soft rubber interposed between the plates and extending along the longitudinal edge portions of the plates as clearly shown in Fig. 3. Preferably sheets 14 of denser rubber

are interposed between the soft rubber cushions and the plates 11 and 12, the sheets being vulcanized to the cushions and to the plates so that the resilient cushions are thus secured to the plates.

The units are shown secured to the conveyer 10 along their transverse median line as by bolts 15, and a pad 16 of metal or other suitable material may be interposed between each unit and the conveyer.

On the base structure of each unit is a top structure for engagement by the bars to be polished. The top structure shown comprises a channel frame 17 having its web secured to the upper plate 11 of the base structure as by means of bolts 18, the side flanges 19 of the channel frame extending upwardly along the longitudinal peripheral portion of the plate 11. Seated in the channel frame between the flanges thereof, is a table 20 in the form of a flat plate or bar which extends longitudinally the full length of the channel frame and which is deflected intermediate its ends as indicated at 21 to provide the high end portion 22 and the lower end portion 23, the higher portion 22 being above the plane of the upper edges of the channel flanges 19 and the lower portion 23 being below this plane, the outer end 24 of the higher portion being deflected downwardly and the outer end 25 of the lower portion 23 being deflected downwardly, these deflected ends forming legs for engaging the web of the channel frame. The table structure may be held against longitudinal displacement on the channel frame as by being welded thereto, or by having one end, such as the end 25 formed to extend into a recess or slot 26 in the channel frame web. The tables 20 receive the ends of the bars B to be polished, the advance ends of the bars resting on the lower decks 23 of the respective tables while the trailing ends of the bars rest on the higher decks of the respective tables. Above the conveyer 10 are the polishing wheels W in engagement with which the bars B are brought as the conveyer travels. To hold the bars against longitudinal displacement under the polishing engagements of the polishing wheels, the upper decks 22 of the table structure may have suitable abutments for the bar ends. As shown, slots 27 may be provided in the upper decks 22 of the tables for receiving the trailing ends of the bars, the advancing ends of the bars resting on the lower decks 23 of the tables between the flanges 19 of the channel structures. The advancing ends of the bars may shift longitudinally on the lower

decks as the bars are deflected vertically under pressure of the polishing wheels. The soft rubber cushions 13 will also yield under such vertical pressure on the bars and thereby eliminate undue strain on the polishing wheels. Furthermore, the soft rubber cushions will permit lateral or tilting movement of the upper plate 11 of the unit base structure and of the bar supporting table structure mounted thereon so that the bars B may tilt or move sideways or sway from one side to the other in order that any portions of the bars in the form of slight twists or warp or other irregularities may be properly presented to the polishing rolls for efficient and uniform polishing of the bars.

Table structures 20 of different shapes may be applied to the unit depending upon the shape and configuration of the bars or other structures to be polished. By means of the resilient 20 and yieldable fixture or supporting structure uniform and accurate polishing will result without strain on the conveyer or the polishing wheel structure, and the bars to be polished can be quickly applied to the units for the successive 25 travel thereof through the polishing fields.

I have shown a practical embodiment of my invention but I do not wish to be limited to the exact construction, arrangement and operation shown and described, as changes and modifications 30 may be made which will still come within the scope of the invention.

I claim as follows:

1. Fixture units to be secured upon the conveyor of a polishing machine and to be spanned 35 by objects to be polished, each unit comprising a lower part to be secured to the conveyor, an upper part for securing the object to be applied to the polishing elements of the polishing machine, and a resilient connection between the

upper and lower parts in the form of pillars of sponge rubber secured only at their ends to said parts with their intermediate portions free to distort whereby said upper part may move freely laterally in all directions to accurately apply the objects thereon to the polishing elements. 5

2. Polishing fixtures for application to the conveyor of a polishing machine and to be spanned by bars to be polished, each fixture comprising a lower part adapted to be secured to the conveyor, an upper part forming a table on which the bars to be polished are supported to be carried for application to the polishing elements of the polishing machine, and blocks of resilient rubber between and secured only at their upper 15 and lower ends to said parts with their intermediate portions free to distort whereby said table part may freely follow all lateral movement of the bars during their longitudinal travel in engagement with the polishing elements. 20

3. A supporting unit for polishing machines comprising a lower part adapted to be secured to the conveyor of a polishing machine, and an upper part for securing an object to be carried by the conveyor for application to the polishing 25 elements of the polishing machine, and a cushion of material having the characteristics of sponge rubber between said parts, said cushion being secured only at its upper and lower ends to said parts with its intermediate portion free to distort whereby said upper part may freely follow any sidewise movement of the object thereon while the object is being carried by the conveyor into application with the polishing elements so that any slight twist, edge warp, or other irregularity in the object may be properly applied to the polishing elements. 30 35
